DENTURE

Robert White Blake, Indianapolis, Ind.

Application June 26, 1933, Serial No. 677,570

10 Claims. (Cl. 32—2)

My invention relates to improvements in dentures and more particularly to improvements in removable dentures. It is one of the objects of my invention to provide a denture which will permit of an adjustment of the denture after the same has been constructed to compensate for the gradual shrinkage of the tissues of the mouth, and particularly of the gums, whereby without rebuilding or reconstruction, this shrinkage of the tissues may be compensated for to maintain the "bite".

Another object of my invention is to provide a denture which will be cushioned to thereby relieve tissues of the mouth from the full force of the bite and thus prevent soreness and pinching of the tissues, particularly of the gums.

Another object of my invention is to provide an improved form of denture which, though removably anchored to an adjoining tooth, will not impose undue strain upon the anchor or the tooth and which may be adjusted after the tissues of the gum have shrunk to prevent undue strain upon the clasp and the clamp or fastening device prevented from affecting the sound tooth or teeth with which the clamp or clamps may be engaged.

Further objects and advantages of my denture will appear more fully in the accompanying specification and claims.

Referring to the drawing forming a part of the specification, and in which certain embodiments of my invention are illustrated,

Fig. 1 is a side elevation of a set of normal teeth, including one form of a removable bridge embodying my invention;

Fig. 2 is a plan view of the bottom teeth showing a removable bridge embodying my invention, applied;

Fig. 3 is a plan view of a foundational saddle of a bridge embodying my invention;

Fig. 4 is a side elevation of the saddle illustrated in Fig. 3;

Fig. 5 is a plan view of the tooth-carrying saddle of a bridge embodying my invention for association with the foundational saddle illustrated in Figs. 3 and 4;

Fig. 6 is a side elevation of the tooth-carrying saddle;

Fig. 7 is a side elevation of the tooth-carrying and foundational saddles assembled;

Fig. 8 is a longitudinal section thereof;

Fig. 9 is a transverse section;

Fig. 10 is a plan view of a bottom set of teeth wherein a bridge for the opposite sides of the mouth is used;

Figs. 11 and 12 are plan views respectively of the two side tooth-carrying saddles for the structure illustrated in Fig. 10;

Fig. 13 is a plan view showing the foundational saddle in position with the tooth-carrying saddle removed;

Fig. 14 is a sectional view of the mouth showing the structure illustrated in Fig. 10 in position;

Fig. 15 is a plan view of a full set of lower teeth embodying my invention, and

Fig. 16 is a plan view of the foundational saddle thereof.

Referring first more particularly to the structure illustrated in Figs. 1 to 9 inclusive, I provide a foundational saddle or plate 1 which is arched and shaped to fit that portion of the gum from which the teeth have been removed. This foundational saddle, in the embodiment illustrated, is provided with a bar 2 having at its opposite end a clasp 3 adapted to embrace a sound tooth on the opposite side of the mouth, the bar being adapted to extend across the mouth behind the front lower teeth. This clasp is provided on its top with a prong or projection 4 adapted to rest on the top of the tooth to prevent the clasp from dropping down on the tooth. Clasp 3 is so arranged that it prevents lateral displacement of the saddle 1 but at the same time permits a limited downward movement of the saddle without throwing undue strain on the clamp or on the tooth which it embraces. This foundational saddle is provided with a series of posts or pins 5, the saddle and its associated parts being formed of any desirable material such as vulcanite, gold or the like, and where the saddle is formed of gold the pins 5 are preferably brazed or soldered in position while, if the saddle is formed of vulcanite, the pins may be embedded therein and baked in position when the vulcanite is hardened. As shown in Figs. 1 and 2, this foundational saddle fits over that portion of the gum from which the teeth have been removed and removably attached to the foundational saddle is a tooth-carrying saddle 6, conforming substantially to the shape of the foundational saddle, and carrying the teeth 7. These teeth are secured to the tooth-carrying saddle in the usual manner and are provided, or at least a portion of the same are provided, with hollow tubes 8 extending throughout the length of the tooth and adapted to accommodate the pins 5 of the foundational saddle. These hollow tubes need not necessarily extend through every tooth mounted on the saddle but at least a sufficient

50

55

number should be provided to make suitable provision for the connecting of the tooth-carrying saddle to the foundational saddle through the instrumentality of the pins and tubes. This 5 tooth-carrying saddle is provided with a clamp 9 adapted to embrace the adjacent sound tooth to prevent longitudinal displacement of the saddle and the clasp is also provided with a prong or projection 10 adapted to rest on the top of the sound tooth to prevent the dropping of the saddle and clasp beyond its predetermined position.

Preferably interposed between the tooth-carrying saddle 6 and the foundational saddle 1 is a 15 shim or cushion 11. This shim or cushion may take various forms and may, as shown in the drawing, extend practically the full extent of the saddle on either side or may, if desired, be comparatively narrow so that it extends a short 20 distance on either side of the center line of the saddles. Or, if desired, this cushion may take the form of small annular rings surrounding each of the posts. The cushion or shim is preferably formed of rubber or any desirable resilient 25 material, although other material, such for instance as any suitable metal, gold, hardened copper, or the like, may be used. The shim has two functions. One, to provide a more or less resilient member interposed between the tooth-carrying and foundational saddle to provide a 30 cushioning effect for the teeth during the mastication process and to provide a means whereby the tooth-carrying saddle may be adjusted in the mouth. Usually in dentures of this nature 35 the tissues of the gums of the wearer shrink for a period after the teeth have been extracted and the denture inserted and as a result the denture will move away from the teeth of the opposite jaw. This not only destroys the bite of the denture but also throws an undue strain on the clamp 9 and an undue pressure on the adjacent sound tooth to which the clasp is attached, thus causing a soreness in the tooth and a gradual loosening of the tooth. With the present structure, as the gums shrink, from time to time, the tooth-carrying saddle with its associated teeth 40 may be removed and a thicker shim 11 inserted, thus moving the top saddle closer to the corresponding teeth of the opposite jaw and compensating for this shrinkage of the gum to preserve the bite of the denture without reconstructing the entire device. Furthermore, not only is the bite preserved, but the absolute position 45 of the clamp 9 is maintained, thus relieving the sound tooth of the strain of a distortion of this clamp.

In the particular construction illustrated in Figs. 1 to 9, inclusive, it will be seen that the bottom edges of the foundational saddle take 50 somewhat of an outward flare as at 12, however, at the same time, conforming to the contour of the gum or gums over which it fits. The tooth-carrying saddle preferably has a small inner bead 13 thrown up on its inner side and the outer surface 55 of the top saddle at its lower edge becomes flush with the outer edge of the bottom saddle, thereby presenting a smooth surface and, by the bead 13 more or less sealing the space between the tooth-carrying and foundational saddles.

In the structures illustrated in Figs. 10 to 14 inclusive, I have shown a structure wherein a two-part denture is provided having plates or foundational saddles 14 for opposite sides of the 75 mouth connected together by a suitable bar 15

which is provided with a guiding and positioning prong 16. In this instance the foundational saddles, as is the case in the structure illustrated in Figs. 1 to 9, are each provided with pins 5a adapted to be received in tubes on the tooth-carrying saddles 17 similar to the tubes shown in Figs. 8 and 9. The tooth-carrying saddles in each instance receive the teeth and each tooth-carrying saddle is provided with a clamp 18 and associated prong 19 similar in construction and function to the parts 9 and 10.

In this construction there is likewise provided a shim 11, as in connection with the structures shown in Figs. 1 to 9 inclusive. In Figs. 15 and 16 I have illustrated an embodiment of my invention in a 15 full lower denture. As shown in this structure, the foundational saddle 20 covers the entire lower gums from which the teeth have been extracted. This saddle is provided with suitable pins 21 and for cooperation with this foundational saddle I preferably provide a tooth-carrying saddle formed in a plurality of sections, as for instance three sections, A, B and C. The teeth are suitably mounted on the three sections and each of the sections is provided with tubes similar to tubes 8 for cooperation with the pins 21. These tubes may extend through all or a few of the teeth of each section and, as illustrated in B, may extend through the teeth proper or, as illustrated in the sections A and C, may extend between the teeth. In this structure, as in connection with the structure illustrated in Figs. 1 to 9, shims as the shims 11, are adapted to be interposed between the tooth-carrying and foundational saddles or plates.

In some instances it may be found, especially when the denture is first used, that a shim of any character may be dispensed with, although I have found in practice that a cushioning shim even in the early stages is advantageous.

The foundational member has been referred to as a saddle but it will be understood that this term is intended to be comprehensive enough to embrace even a plate such as is used for a full set of upper teeth.

I claim as my invention:

1. A removable denture comprising in completed form a foundational saddle adapted to bear on the gums, a tooth-carrying saddle vertically movable on said foundational saddle having one 50 or more artificial teeth mounted thereon and means secured to the foundation saddle engaging the teeth of the tooth-carrying saddle and holding the same against lateral displacement while permitting vertical movement.

2. A removable denture comprising in its completed form, a foundational saddle adapted to bear on the gums, vertically extending pins mounted on said foundational saddle, a tooth-carrying saddle, one or more artificial teeth 60 mounted on the tooth-carrying saddle and provided with tubular members removably receiving said pins, said tubular members being embraced by the teeth on the tooth-carrying saddle.

3. A removable denture comprising in its completed form, a foundational saddle adapted to bear on the gums, vertically-extending pins mounted on the foundational saddle, a tooth-carrying saddle resiliently supported on the foundational saddle, one or more teeth mounted on the 70 tooth-carrying saddle, and tubular members on said tooth-carrying saddle receiving said pins and embraced by the teeth of the tooth-carrying saddle.

4. A removable denture comprising in its com-

- pleted form, a foundational saddle adapted to bear on the gums, vertically extending pins mounted on the foundational saddle, a tooth-carrying saddle, one or more teeth secured to the 5 tooth-carrying saddle, tubular members receiving said pins mounted on said tooth-carrying saddle and embraced by the teeth, and a shim interposed between the tooth-carrying and foundational saddles.
- 10 5. A removable denture comprising in its completed form a foundational saddle adapted to bear on the gums, vertically-extending pins mounted on the foundational saddle, a tooth-carrying saddle having one or more teeth 10 secured thereon provided with tubular members for receiving said pins embraced by the teeth of the tooth-carrying saddle, and a resilient shim interposed between the tooth-carrying and foundational saddles.
- 15 6. A detachable denture comprising in its completed form, a foundational saddle adapted to bear on the gums, vertically-extending pins mounted in said foundational saddle, a tooth-carrying saddle having one or more teeth 15 mounted thereon and having tubular members embraced by the teeth receiving said pins and means for anchoring said tooth-carrying saddle to a sound tooth in the mouth.
- 20 7. A removable denture comprising in its completed form a foundational saddle adapted to bear on the gums, vertically-extending pins secured to said saddle, a tooth-carrying saddle having one or more teeth secured thereon and provided with tubular members receiving said pins and 20 embraced by the teeth on said tooth-carrying saddle, a clamp on said tooth-carrying saddle for embracing a sound tooth in the mouth and means for anchoring said foundational saddle to a sound tooth against lateral displacement.
- 25 8. A full denture comprising a one-piece foun- 25 dational saddle adapted to embrace and bear upon the gums, receiving pins extending from said saddle, and a tooth-carrying saddle comprising a plurality of sections separably supported upon said foundational saddle in final assembly, each section having a pin-receiving socket slidably receiving a pin on the foundational saddle and maintaining said tooth-carrying saddle from lateral displacement on the foundational saddle while permitting a vertical movement between 10 said saddles and the separation of said saddles.
9. A full denture comprising a one-piece foundational saddle adapted to embrace and bear upon the gums, receiving pins extending from said saddle, a tooth-carrying saddle comprising 15 a plurality of sections separably supported on said foundational saddle in final assembly, each section having a pin-receiving socket slidably receiving a pin on the foundational saddle and maintaining said tooth-carrying saddle from lateral displacement on the foundational saddle and permitting a relative vertical movement between 20 and vertical separation of said saddles and a shim interposed between one or more of said sections and the foundational saddle.
10. A full denture comprising a one-piece foundational saddle adapted to embrace and bear upon the gums, receiving pins extending from said saddle, a tooth carrying saddle comprising a plurality of sections separably supported on 30 said foundational saddle in final assembly, each section having a pin-receiving socket slidably receiving a pin on the foundational saddle and maintaining said tooth carrying saddle against lateral displacement on the foundational saddle 35 while permitting a relative vertical movement between and separation of said saddles and resilient shims interposed between one or more of said sections and the foundational saddle.
